UNITED STATES PATENT OFFICE.

ARTUR EICHLER, OF ZOSSEN, GERMANY, ASSIGNOR, BY MESNE ASSIGNMENTS, TO MERGENTHALER LINOTYPE COMPANY, A CORPORATION OF NEW YORK.

MATRIX-SETTING AND TYPE-LINE-CASTING MACHINE.

1,143,370.

Specification of Letters Patent. Patented June 15, 1915.

Application filed September 7, 1910. Serial No. 580,911.

To all whom it may concern:

Be it known that I, ARTUR EICHLER, residing at Zossen, in the Kingdom of Prussia and State of Germany, have invented 5 certain new and useful Improvements in Matrix-Setting and Type-Line-Casting Machines, of which the following is a specification.

This invention relates to a casting mold 10 for matrix setting and line casting machines, by means of which the casting slot can be accurately set to given fractions of typographic measuring units.

In the accompanying drawing: Figure 1 15 is an elevation of the casting mold, seen from the front; Fig. 2 is the left hand portion of Fig. 1 after the casting slot has been narrowed to the extent of $\frac{1}{2}$ pica; Fig. 3 is the part for fixing the intermediate part of 20 a somewhat different construction.

The casting mold consists as usual of the mold body having a bottom or lower part *a* and a top or upper part *b*, both of which extend longitudinally, and of the two intermediate parts or liners *c* and *d*, one of which, *c*, is fixed, and the other one *d* mounted in an adjustable manner. The top and bottom surfaces of the casting made in said mold are defined by the parallel opposed surfaces 25 of the upper and lower mold parts, while one end surface of the casting is defined by the vertically extending surface at one end of the fixed intermediate part *c* and the other end surface of the casting is defined 30 by the vertically extending surface at one end of the adjustable intermediate part *d*. In other words, the resulting casting is a strip of metal the top and bottom surfaces of which are parallel, but the length of 35 which is dependent upon the position of the intermediate part or liner *d*. The intermediate part *d* is provided with a number of transversely extending grooves *e* the width of which is equal to one half of the usual 40 typographic measuring unit. This intermediate part *d* constitutes a liner between the bottom part *a* and upper part *b* and is adjustable longitudinally. For German or 45 United States conditions, the width of the groove would be made equal to $\frac{1}{2}$ pica. The tenon remaining between two grooves, is of the same width as the groove, so that the pitch *f* is equal to one typographic measuring unit. For fixing the intermediate part 50 *d* in the casting mold, is used a prismatic

key *g* arranged in a slot of the upper or bottom part of the casting mold. The width *h* of the said key is also equal to the typographic measuring unit, however, the width of the part of the key projecting over the surface of the upper or bottom portion of the casting mold is equal to half the typographic measuring unit, the said projection engaging with the grooves above referred to of the intermediate part, and holding the latter fast. If the key is left in the position shown in Fig. 1 it is possible to shift the intermediate part to the extent of one measuring unit owing to the pitch of the grooves. If, however, the key *g* is turned as shown in Fig. 2 then the part of the key engaging with the intermediate mold portion will be removed to the left to the extent of half a measuring unit, and consequently the intermediate part can be adjusted to the extent 60 of half the measuring unit. The key, however, can also be made of the shape shown in cross-section in Fig. 3. It will be noted that the key shown in Fig. 1 can be positioned as shown in Fig. 2 or even have substituted in place thereof a key such as is shown in Fig. 3. In other words, these keys are interchangeable. In any case, the dimension *h* must be equal to the typographic measuring unit, or to a multiple thereof, and 65 the width of the projection equal to $\frac{1}{2} h$.

By arranging the projection in a different manner on the surface of the key, it is possible also to obtain an adjustment for other fractions of the measuring unit. If, as 70 shown for instance in Fig. 3, the dimension *k* is made equal to $3/8 h$ and the dimension *l* equal to $1/8 h$, then, if such a key is reversed, the part of the key engaging with the intermediate mold portion would be 75 moved to the extent of one quarter of the measuring unit. If the dimension *k* is made equal to $5/12 h$, and the dimension *l* equal to $1/12 h$, then there would be an adjustment to the extent of $4/12$ or $1/3$. By a 80 suitable arrangement of the upper key portion, it is, therefore, possible to obtain an adjustment of the intermediate part to any desired fraction of the measuring unit. The same adjustment could of course be obtained 85 by arranging the grooves in the upper or bottom portion of the casting mold, and the key in the intermediate part. It will be noted that the portion of the key which projects above the surface of the lower body 90

part *a* of the mold constitutes a holding portion which engages the adjustable intermediate member while that portion of the key which is located in the slotted portion 5 of the lower body part constitutes a holding portion which engages the base. Thus said holding portions of the key directly coöperate with the intermediate and body parts to hold the intermediate part in place relative to the body part. It will also be observed that the holding portion of the key which engages the intermediate member is of a different width than the holding portion of the key which engages the body part 10 *a* and also that said holding portions are unsymmetrically arranged. When the key, rib or member *g*, as it may be called, is holding the liner *d* in the desired adjusted position between the upper part *b* and the lower part *a* of the mold it is mounted in a fixed position, so to speak, in the lower part *a* when the mold is constructed as shown. So far as the function of holding the intermediate liner against longitudinal movement, this key, rib or member acts the same 15 as the projection thereof would act if made an integral portion of the lower part *a*.

It will furthermore be noted that my improved construction of the parts is not only useful in securing different adjustments of the mold, but also in connection with the manufacture of the parts. For instance, heretofore the liners have been made with transverse ribs, and the mold parts formed 20 with grooves to receive such ribs and keep the liners in proper position. The manufacture of these liners is troublesome and expensive, involving the cutting away of much metal in order to produce the transverse ribs. In the present construction, the ribs are made separate from the liners, and the latter are formed with grooves wherein the ribs engage, thus allowing the liners to be made quickly, easily and at little cost. 25 It is obvious that this feature of construction is just as applicable to molds employing removable or interchangeable liners as to molds employing adjustable liners as shown herein. That is to say, it is immaterial whether a liner be formed with a series of transverse grooves or with a single groove in which the rib may engage, the invention in this regard residing in the employment of a transverse rib seated in one 30 of the mold parts and adapted to engage in a transverse groove in the liner so as to hold it in proper position.

Having now particularly described and ascertained the nature of my said invention and in what manner the same is to be performed, I declare, that what I claim is

1. A casting mold for matrix setting and type line casting machines consisting of a mold box having an upper part and a bottom part, of two intermediate parts, one of

the intermediate parts being fixed and the other adjustably arranged, and a reversible key connecting the adjustable part with the mold body and engaging with notches of the said parts, the width of the key portion 70 engaging with the intermediate part being different from the width of the key portion engaging with the mold body.

2. A casting mold for matrix setting and type line casting machines consisting of a mold box having an upper part and a bottom part, of two intermediate parts, one of the intermediate parts being fixed and the other adjustably arranged, and a reversible key connecting the adjustable part with the mold body and engaging with notches of the said parts, the width of the key portion 75 engaging with the one mold part being a given fraction of the width of that portion engaging with the other part, substantially as described.

3. A casting mold for matrix setting and type line casting machines consisting of a mold box having an upper part and a bottom part, of two intermediate parts, one of the intermediate parts being fixed and the other adjustably arranged, and a reversible key connecting the adjustable part with the mold body and engaging with notches of the said parts, the width of the key portion 80 engaging with the one part corresponding to a typographic measuring unit and being a given multiple of the width of that portion engaging with the other part, substantially as described.

4. A casting mold for matrix setting and type line casting machines consisting of a mold box having an upper part and a bottom part, of two intermediate parts, one of the intermediate parts being fixed and the other 85 adjustably arranged, and a reversible key connecting the adjustable part with the mold body and engaging with notches of the said parts, the width of the key portion engaging with the one part corresponding to a fraction of a typographic measuring unit and being a given fraction of the width of that portion 95 engaging with the other part, substantially as described.

5. A casting mold for matrix setting and type line casting machines consisting of a mold box having an upper part and a bottom part, of two intermediate parts, one of the intermediate parts being fixed and the other adjustably arranged, and a reversible key connecting the adjustable part with the mold body and engaging with notches of the said parts, the width of the key portion 105 engaging with the one mold part being a given fraction of the width of that portion engaging with the other part, the two key portions being arranged unsymmetrically relatively to each other, substantially as described.

6. A casting mold for matrix setting and

type line casting machines consisting of a mold body having an upper part and a bottom part, of two intermediate parts, one of the intermediate parts being fixed and the other adjustably arranged and a key connecting the adjustable part with the mold body and engaging with notches of the said parts, the width of the key portion engaging with the one mold part being a given fraction of the width of that portion engaging with the other part, the two portions being arranged unsymmetrically relatively to each other in such a way that by turning over the key in the one part of the mold the key portion engaging with the other mold part is shifted in the direction of or away from the casting slot.

7. A casting mold for matrix setting and type line casting machines consisting of a mold body having an upper part and a bottom part, of two intermediate parts, one of the intermediate parts being fixed and the other adjustably arranged and a key connecting the adjustable part with the mold body and engaging with notches of the said parts, the width of the key portion engaging with the one part corresponding to a typographic measuring unit and being a given multiple of the width of that portion engaging with the other part, the two key portions being arranged unsymmetrically relatively to each other in such a way that by turning over the key in the one part of the mold the key portion engaging with the other mold part will be shifted in the direction of or away from the casting slot to a desired fraction of the total width of the key, substantially as described.

8. A casting mold for matrix setting and type line casting machines consisting of a mold box having an upper part and a bottom part, of two intermediate parts, one of the intermediate parts being fixed and the other adjustably arranged, and a reversible key connecting the adjustable part with the mold body and engaging with notches of the said parts, the width of the key portion engaging with the one mold part being different from the width of that portion engaging with the other mold part, one of the said mold parts having a plurality of grooves, substantially as described.

9. A casting mold for matrix setting and type line casting machines consisting of a mold box having an upper part and a bottom part, of two intermediate parts, one of the intermediate parts being fixed and the other adjustably arranged, and a reversible key connecting the adjustable part with the mold body and engaging with notches of the said parts, the width of the key portion engaging with the one mold part being different from the width of that portion engaging with the other mold part, one of the said mold parts having a plurality of

grooves, the pitch of which corresponds to the thicker key portion and the width of which corresponds to the thinner key portion, substantially as described.

10. A casting mold for matrix setting and type line casting machines consisting of a mold box having an upper part and a bottom part, of two intermediate parts, one of the intermediate parts being fixed and the other adjustably arranged, and a reversible key connecting the adjustable part with the mold body and engaging with notches of the said parts, the width of the key portion engaging with the one mold part being different from the width of that portion engaging with the other mold part, one of the said mold parts having a groove corresponding to the thicker key portion and the other mold part having a plurality of grooves, the pitch of which corresponds to the thicker key portion and the width of which corresponds to the thinner key portion, substantially as described.

11. A casting mold for matrix setting and type line casting machines consisting of a mold body having an upper part, a bottom part, intermediate parts, at least one of which is adjustable and a removable key connecting the adjustable part with the mold body and engaging notched portions of said adjustable part and said body, the width of the key holding portion which engages with the adjustable part being different from the width of the holding portion which engages the mold body, the two portions of the key which are of different widths being unsymmetrically arranged relative to each other in such a way that by turning the key in the mold body it will hold the adjustable part in a different position.

12. A slotted mold comprising opposed parts, and an intermediate liner adjustable to vary the length of the slot, together with a key carried by one of the mold parts to hold the liner in its adjusted position, the said key being so mounted in the mold part as to require its removal or detachment therefrom to permit the adjustment of the liner.

13. A slotted mold comprising opposed parts, and an intermediate liner adjustable to different positions to vary the length of the slot, together with an interchangeable element or key to hold the liner in its adjusted position, said key being replaceable by a key of unlike form which holds the liner in a different adjusted position.

14. A slotted mold comprising opposed parts, and an intermediate liner adjustable to vary the length of the slot, together with a key provided with holding portions offset with respect to each other engaging the liner and one of the mold parts respectively.

15. A slotted mold comprising opposed parts, and an intermediate liner adjustable

- to different positions to vary the length of the slot, the liner and one of the mold parts being each formed with a notch or recess, and a key having portions which engage in said notches when the liner is in one adjusted position, the said key being replaceable by a key of unlike form which holds the liner in a different adjusted position by its engagement in said notches.
16. A slotted mold comprising opposed parts, and an intermediate liner adjustable to different positions to vary the length of the slot, the liner and one of the mold parts being each formed with a notch or recess, and a key having holding portions which engage in said notches in different adjusted positions of the liner.
17. A slotted mold comprising an element adapted to occupy a definite location in relation thereto, and having a single projecting portion which may be presented in different positions lengthwise of the slot, in any given location of said element in order to vary the length of the slot.
18. A slotted mold comprising opposed parts, and an intermediate liner to vary the length of the mold slot, together with a connecting element for said liner, the said element having a single projecting portion adapted to be presented in different positions lengthwise of the slot in any given location of the element, so as to vary the position of the liner within the slot.
19. In a mold comprising longitudinally extending top and bottom parts and a longitudinally adjustable liner having formed in one face thereof a transversely extending groove, a transversely extending rib or member which is mounted fixedly on one of said mold parts and which engages in said groove so as to hold the liner against longitudinal movement when the liner is in the desired adjusted position between said mold parts.
20. A mold comprising top and bottom parts and a grooved liner, said top and bottom parts having opposed parallel surfaces that define the shape of the top and bottom surfaces of the casting made in the mold, the liner being located between said opposing surfaces and arranged so that the vertically extending surface at one end of the liner defines one end of the casting; said liner being provided with grooves extend-
- ing transversely thereof, the mold also having a transversely extending rib or member mounted fixedly on one of the mold parts and engaging a grooved portion of said liner to hold the latter in the desired position between said mold parts.
21. A slotted mold comprising opposed parts, and an adjustable intermediate liner to vary the length of the mold slot, together with a reversible element having a single projecting portion to hold the liner in different positions when the reversible element is in its reversed position.
22. A slotted mold comprising opposed parts, and an intermediate liner adjustable to different positions to vary the length of the slot, the liner and one of the mold parts being each formed with a notch or recess, and a removable key having holding portions which engage in one set of notches to hold the liner in one adjusted position and also in the same set of notches to hold the liner in a different adjusted position.
23. A mold comprising top and bottom parts, an intermediate liner formed in one of its side faces with a transverse groove, and a transverse rib or member mounted fixedly on one of the mold parts and engaging in said groove to hold the liner firmly in position.
24. A mold comprising top and bottom parts, and an intermediate liner, the said liner and one of the mold parts being provided in their adjoining faces with transverse grooves, together with a transverse rib or key engaging in said grooves and serving by said engagement to prevent the longitudinal movement of the liner.
25. A mold comprising top and bottom parts, and an intermediate liner, the said liner and one of the mold parts being provided in their adjoining faces with transverse grooves, together with a transverse rib or key engaging in said groove and serving by such engagement to prevent the movement of the liner, said key being removable at will to permit the movement of the liner.
